DESIGN FOR A SLIPPER

Herman L. Prossack, Philadelphia, Pa., assignor to Jerome H. Louchheim, Jr., doing business as Keystone Slipper Company, Philadelphia, Pa.

Application November 25, 1938, Serial No. 81,335

Term of patent 3½ years

To all whom it may concern:

Be it known that I, Herman L. Prossack, a citizen of the United States, residing at Philadelphia, in the county of Philadelphia and State of Pennsylvania, have invented a new, original, and ornamental Design for a Slipper, of which the following is a specification, reference being had to the accompanying drawing, forming part thereof.

I claim:
The ornamental design for a slipper, as shown.

HERMAN L. PROSSACK.
